UNITED STATES PATENT OFFICE.

HERBERT PHILIPP AND HANS FOERSTERLING, OF PERTH AMBOY, NEW JERSEY.

PROCESS OF MAKING CYANOGEN COMPOUNDS.

1,249,821.

Specification of Letters Patent. Patented Dec. 11, 1917.

Original application filed June 2, 1910, Serial No. 564,672. Divided and this application filed June 4, 1912, Serial No. 701,570. Renewed May 11, 1917. Serial No. 168,045.

To all whom it may concern:

Be it known that we, HERBERT PHILIPP, a citizen of the United States, and HANS FOERSTERLING, a subject of the Emperor of Germany, both residing at Perth Amboy, Middlesex county, New Jersey, have invented certain new and useful Improvements in Processes of Making Cyanogen Compounds, of which the following is a specification.

10 This invention relates to a method of making cyanogen compounds by vaporizing a metal capable of forming cyanogen compounds and reacting the vaporized metal with nitrogenous and carbonaceous matter 15 and is a division of a pending application filed June 2, 1910, Serial No. 564,672.

In United States Letters Patent No. 993,391, dated May 30, 1911, McNitt has disclosed a method for reducing metals, 20 based on the electrolysis of metallic compounds, the alloying of the separated metal with the cathode metal and the separating of the two metals by passing a current of inert gas through the hot alloy whereby the 25 more volatile metal is vaporized.

We have found that, with a metal capable of forming cyanogen compounds and with nitrogen as the inert gas, the passing of the volatile metal vapors together with the nitrogen through a furnace containing carbon, 30 easily forms cyanogen compounds.

In United States Patent No. 914,100, Acker has disclosed a process of producing cyanogen compounds by electrolyzing a 35 molten compound of a metal, alloying the separated metal with the cathode metal, removing the alloy from the electrolytic cell and reacting on the alloyed metal with nitrogenous and carbonaceous reagents.

40 Our method differs from Acker's in that we first separate the volatile metal from the cathode metal and then bring the volatile metal in contact with nitrogenous and carbonaceous matter.

45 In the following we have described, in connection with the accompanying drawing, one way of practising our process, the features thereof being more particularly pointed out hereinafter in the claims.

50 The drawing is a diagrammatic sectional view of a form of apparatus illustrating one way of carrying out our process and in connection therewith we shall describe our process as applied for instance to the pro-

duction of an alkali cyanid such as sodium 55 cyanid.

We electrolyze sodium chlorid in the presence of a suitable cathode metal such as lead, in any well-known manner and obtain an alkali metal alloy, specifically sodium lead 60 alloy, as described by McNitt in his United States Patent No. 993,391 for instance. As McNitt has fully described his cell in the patent referred to, we shall not describe it here further than that the reference numeral 65 1 indicates the electrolytic chamber; 2 indicates the furnace chamber; 3 indicates a transverse partition extending from side to side of the chamber 1 leaving an opening 4 at one end between the end of the partition 70 and the wall of chamber 1, the other end of partition 3 being bent so as to form a seal 5 into which depends end wall 6 of chamber 1. 7, 7 indicate the anodes, 8 the cathode metal, molten lead for instance, 9 the electrolyte, 75 sodium chlorid for instance, 10 a pipe for conducting an inert gas, such as nitrogen, to a point beneath the surface of the contents of furnace chamber 2 and 11 indicates a furnace for heating furnace chamber 2. In the 80 operation of the cell as described the sodium is separated from the chlorin, which latter passes off in the usual manner, and is alloyed with the cathode metal. The alloy is caused to circulate out of chamber 1 through seal 5 85 into furnace chamber 2, as described by McNitt, where it is maintained at a suitable temperature and subjected to the action of the inert gas which passes through the same, the gas carrying the sodium vapor through 90 connection 12 into retort 13, heated in any suitable manner (not shown), the remaining portion of the molten alloy, freed from some or all of the sodium, being drawn through 95 channel 14 and opening 4 into chamber 1 where the residual metal again serves as the cathode and the operation repeated.

The sodium lead alloy is kept at such a temperature in chamber 2 as to permit the inert gas, specifically nitrogen, to be introduced therein without reaction therewith so that the gas may carry off the sodium vapor as a metal *per se* as described. The retort 13 is kept at such a temperature that the sodium vapors combine in the presence of 100 nitrogen and charcoal to form sodium 105 cyanid.

The carbonaceous material in retort 3

rests on a grate 15 through which the alkali cyanid, formed as described, drips into the drum 16 of the retort and is thence permitted to flow off in any suitable manner, as 5 through outlet 17. Fresh charcoal is added from time to time as required. Very little fuel is required in practising our process as the formation of cyanid takes place at not much above the temperature at which the 10 electrolysis takes place.

It is to be understood that we do not limit ourselves to the process as described. The metal from which the cyanid is formed may be produced without intermediate formation 15 of an alloy, for instance sodium chlorid may be electrolyzed by a diaphragm process and the sodium directly vaporized with nitrogen; instead of blowing nitrogen into the alloy, hydrogen or other inert gas may be 20 used and the process may be carried out in two steps if desired.

What we claim and desire to secure by Letters Patent is:

1. The method of making cyanogen compounds consisting in vaporizing a metal capable of forming cyanogen compounds and reacting upon said metal while in the 25 vaporous state with nitrogenous and carbonaceous matter.

2. The method of making cyanogen compounds consisting in vaporizing a metal capable of forming cyanogen compounds in the presence of a current of nitrogen and reacting upon said mixture while in a vapor- 30 ous state with carbonaceous matter.

3. The method of making sodium cyanid consisting in vaporizing the sodium and reacting upon the sodium while in a vaporous state with nitrogenous and carbonaceous 35 matter.

4. The method of making sodium cyanid consisting in vaporizing the sodium in the presence of a current of nitrogen and reacting upon the sodium nitrogen vapors while 45 in the vaporous state with carbonaceous matter.

5. The method of making cyanogen compounds consisting in vaporizing a metal capable of forming cyanogen compounds 50 from a molten mass containing the same, conducting the metal while in the vaporous

state to a retort separate from the vaporizing chamber and reacting upon the same in the retort with nitrogenous and carbonaceous matter.

6. The method of making cyanogen compounds consisting in vaporizing, in a current of nitrogen, a metal capable of forming cyanogen compounds from a molten mass containing the same, conducting the mixture 60 while in the vaporous state to a retort separate from the vaporizing chamber and reacting upon the same in the retort with carbonaceous matter.

7. The method of making cyanogen compounds consisting in vaporizing a metal capable of forming cyanogen compounds, conducting the metal while in the vaporous state to a retort separate from the vaporizing chamber and reacting upon the same 70 in the retort with nitrogenous and carbonaceous matter.

8. The method of making cyanogen compounds consisting in vaporizing, in a current of nitrogen, a metal capable of forming 75 cyanogen compounds, conducting the mixture while in the vaporous state to a retort separate from the vaporizing chamber and reacting upon the same in the retort with carbonaceous matter.

9. The method of making sodium cyanid consisting in vaporizing molten sodium metal, conducting the metal while in the vaporous state to a retort separate from the vaporizing chamber and reacting upon the same 85 in the retort with nitrogenous and carbonaceous matter.

10. The method of making sodium cyanid consisting in vaporizing molten sodium metal in the presence of nitrogen, conducting the sodium nitrogen mixture while in the vaporous state to a retort separate from the vaporizing chamber and reacting upon the same in the retort with carbonaceous matter.

In witness whereof, we have signed this 95 specification in the presence of two subscribing witnesses.

HERBERT PHILIPP.
HANS FOERSTERLING.

ARNOLD NORMENBERG.

Correction in Letters Patent No. 1,249,821.

It is hereby certified that Letters Patent No. 1,249,821, granted December 11, 1917, upon the application of Herbert Philipp and Hans Foersterling, of Perth Amboy, New Jersey, for an improvement in "Processes of Making Cyanogen Compounds," were erroneously issued to the inventors, said Philipp and Foersterling, whereas said Letters Patent should have been issued to *The Roessler & Hasslacher Chemical Co., of New York, N. Y., a corporation of New York*, as shown by the records of assignments in this office; and that the said Letters Patent should be read with this correction therein that the same may conform to the record of the case in the Patent Office.

Signed and sealed this 19th day of March, A. D., 1918.

[SEAL.]

R. F. WHITEHEAD,

Acting Commissioner of Patents.
